UNITED STATES PATENT OFFICE.

GEORGE C. BOOTON, OF UNION BRIDGE, MARYLAND.

AUTOMATIC ENGINE STOP.

Application filed February 21, 1922. Serial No. 538,177.

To all whom it may concern:

Be it known that GEORGE C. BOOTON, a citizen of the United States, residing at Union Bridge, in the county of Carroll and State of Maryland, has invented certain new and useful Improvements in Automatic Engine Stops, of which the following is a specification.

This invention relates to a safety stop for steam engines and aims primarily to provide means for automatically cutting off the supply of steam to the engine when the engine is subject to extra load or where there is a tendency for it to race.

The invention also contemplates the cutting off of steam to the engine upon injury to the governor, for instance, such as the governor belt parting, as would render the latter inoperative.

A further object of my invention is to automatically shut off the steam from the engine upon dropped load or pull switch.

A still further object of my invention is to so construct the safety mechanism that it may be automatically equipped or actuated to cut off the supply of steam to the engine without the necessity of operating the throttle valve, so that should the throttle valve be located in the vicinity of escaping steam or should it become expanded due to heat so as to be difficult to turn, the shutting off of the steam supply may be accomplished without risk on the part of the engineer.

And a still further object of my invention is to provide an automatic cut off mechanism, of the type mentioned which may be assembled with any ordinary steam engine and its governor without any material change in the construction of the governor.

The above objects of my invention are accomplished through the novel arrangement and construction of parts, wherein I employ an extra reach rod between the valve operating lever and intake valve, which is adapted to be broken at a joint adjacent one end of same, upon breakage of the governor belt, over speeding of the engine, or upon drop load or pull switch, thus automatically breaking the means for operating the intake and exhaust valves, thereby shutting off steam to the engine.

These and like objects of my invention will be better understood as the description proceeds, and as specifically pointed out in the appended claims.

Referring to the accompanying drawings, which form a part of this specification, and which clearly illustrate the construction of my invention—

Figure 1 is a side elevation of an engine provided with my improvement.

Figure 2 is a similar view with a portion of the engine broken away and showing the valve operating mechanism of the engine in an inoperative position, due to the breaking of the governor belt.

Figure 3 shows the position of an electric magnetic switch control when in a running position.

Figure 4 shows a similar view of the electric magnetic switch control when same has a drop load or pull switch.

Figure 5 is a similar view of the electric magnetic switch control when the governor belt has broken.

Figure 6 is a fragmentary detail view of the reach rod connection with the electric magnetic switch.

Figure 7 is a detail side elevation of the reach rod breaker in a running position.

Figure 8 is a plan view of same with a portion of the reach rod sockets broken away to better illustrate my invention.

Figure 9 is a side elevation of the reach rod breaker in a position, such as same would assume upon breakage of the governor belt, over speeding of the engine or a pull switch.

Figure 10 is a detail side elevation of the valve operating mechanism and my improved reach rod and reach rod breaker connected thereto, showing same in a running position.

Figure 11 is a similar view showing the valve mechanism, reach rod and reach rod breaker in an inoperative position.

Figure 12 is a fragmentary detail view of the supporting rod and belt roller for throwing the valve mechanism, reach rod, reach rod breaker into an inoperative position, for shutting off steam to the engine when the governor belt breaks.

Referring to the drawings in detail, like numerals will be used to designate like parts in the different views.

While in the drawing there is shown a specified form of governor, although of a well known type and a specified valve controlling mechanism, it will be readily understood that the safety stop mechanism

embodying the present invention may be assembled with any other similar form of governor and any other similar form of valve controlling mechanism.

5 Referring to the drawings in detail, the numeral 1 represents the engine, mounted on a base 2, and provided with intake and exhaust ports 3, rod plates 4, which are connected to the exhaust and intake valve levers or connecting rods 5, all of which are of the usual construction and for which no claim is herein made.

10 The coreless governor of the usual revolvable type is represented at 6 as mounted upon shaft 7 and supported by the vertical standard 8. The governor is driven by a pulley 9 and a belt 10 from the engine shaft in the usual manner. Attached to the vertical standard 8 in any suitable manner is an electric magnet 11, in the end of which a carrier armature rod 12 slides. A second carrier rod 13 is provided with a reduced end 14, which is adapted to slide in the hollow carrier rod 12 and is secured therein by means of a pin 15, which will be hereinafter further described. The carrier rod 13 is movably supported in a bracket 16 carried by the vertical standard 8. The lower end of the carrier rod 13 is bifurcated as at 17 and between the bifurcated ends 17 is journaled a roller 18.

15 A supporting rod 19 is pivotally connected as at 20 to the vertical standard 8 by the bracket 21. Secured to the pulley shaft 22 is a bracket 23 to which is connected a rod 24. A plate 25 is securely mounted on one end of the rod 24 and has a cript rod 26 carried by the other end of the plate 25. The cript rod 26 bears in engagement 20 with the supporting rod 19 adjacent the lower end of same. On the free end of the rod 24 is connected an arm 27, which is provided with a spindle 28 on which is mounted a roller 29 adapted to ride on the governor belt 10 as indicated in Fig. 1.

25 A valve operating lever 30 is pivoted as at 31 to a bracket 32 carried by the vertical standard 8. Connected with the upper end of the valve operating lever 30 is the upper reach rod 33 which is connected with the steam inlet valve mechanism as at 34. The upper reach rod 33 is provided with a hinge 35 adjacent the end where same connects with the valve operating lever 30.

30 55 The lower end of the valve operating lever is connected with a lower reach rod 36, which is connected at the opposite end to a reach rod breaker designated as a whole by the numeral 37, which in turn is connected to the vertical valve mechanism of one of the intake ports as shown at 38. The upper and lower reach rods are connected by the coupling rod 39. A coil spring 40 is connected to the rod 39 adjacent the connection with the upper reach rod, and the

opposite end of the spring is connected to the valve operating lever 30.

35 The supporting rod 19 has an arm 41 formed integral at a point above the pivot connection 20. The arm 41 is formed at right angle to the supporting rod and has pivotally connected as at 42 a link 43, to the free end of which the pin 15 is pivotally connected.

40 An extra reach rod 44 is connected at 75 one end to the reach rod breaker 37 and the opposite end of the extra reach rod is provided with an enlarged head 45 which passes through the bifurcated end 17 of the carrier rod 13 and rests on and in engagement 80 with the roller 18 that is journaled in the bifurcated end 17.

45 The reach rod breaker 37 comprises socket members 46, 47 and 48. Each of the socket members is provided with screw threads so that adjustment of the reach rod 36, the extra reach rod 44, and the short valve mechanism rod 49 can be made. The lower reach rod 36 screws into the screw threaded socket 46, while the extra reach rod 44 is screw threaded in the socket 47. The socket members 46 and 48 are hingedly connected at 50. The upper surface of the socket member 46 is provided with a pair of lifts 51—51 to which is pivotally supported by the pivot 52, a link comprising arms 53—53 which depend downwardly on each side of the member 46, and a roller 54 is journaled between the free ends of the arms 53 beneath the member 46, as illustrated in Fig. 7.

50 A downwardly suspending arm 55 is formed integral with the member 46, and has a roller 56 mounted on a spindle 57 carried by the end of the arm 55. The socket member 48 has a connecting arm or rod 58 pivotally connected as at 59 to the underside of same. The free end of the arm or rod 58 is provided with a roller engaging recess 60, so that when the engine is in a running position the arm or rod 58 lies in a parallel line with the socket members 46 and 48, and the roller engaging recess 60 of the arm 58 rests on the roller 54 that is positioned between the free end of the downwardly suspending arms 53—53.

55 The socket member 47 is pivotally connected to one of the downwardly suspending arms 53 and when the engine is running the member 47 lies in approximately a parallel line with the socket member 46. The socket member 47 is approximately of L-shaped formation, and the part 61, which is at right angle to the socket 47 is provided with a curved end 62 which bears against the roller 56 and which acts as a trip to uncouple the members 46 and 48 from the position shown in Fig. 7 upon breakage of the governor belt, overspeeding of the engine or pulled switch.

While, as before stated, the mechanism embodying the present invention may be assembled with any ordinary valve controlling mechanism, and while no claim is made for the valve controlling mechanism shown in the drawing, it is thought that a brief description as to the operation and construction of same will give a better understanding as to the operation and construction of my automatic engine stop; therefore, the valve controlling mechanism shown in the accompanying drawings as clearly illustrated in Figs. 10 and 11 include an arm 38, to which is connected a rod 49 which is connected to the reach rod breaker 37, which in turn is connected to one end of the valve operating lever 30. At this point it will be understood that the rocking movement imparted to the lever 30 will result in corresponding movement of the arm 38. The arm 38 is formed or provided with a cam 63 which is of course movable therewith. An arm 64 is mounted upon the shaft 65, upon which the arm 38 is also mounted, and is arranged to move the steam valve to cut off or admit steam to the engine cylinders.

The bracket 16 mounted on the vertical standard 8 is provided with a shoulder 16', against which the bifurcated end 17 of the lower carrier rod 13 bears and prevents rotation of the carrier rods 12 and 13 while the engine is in a running position, or when the carrier rods are in the position shown in Fig. 3.

As hereinbefore stated, the object of my invention is to automatically stop an engine upon breakage of the governor belt, over speeding of the engine, drop load or pulled switch, and in case of breaking of the governor belt, the following operation takes place. When the governor belt breaks, the roller 29 journaled on the end of the arm 27 drops downwardly and assumes the position shown in Fig. 2, and on the downward travel of the roller and arm, the trip arm 26 presses firmly against the lower end of the supporting rod 19, which causes same to swing on the pivot 20, thus moving the pivoted arm 43 outwardly from the vertical standard and at the same time withdrawing the pin 15 from the aligned opening in the carrier rods 12 and 13. When the pin 15 has been entirely withdrawn, the carrier rod 13 falls to the position shown in Fig. 5, and the dropping of the carrier rod 13 permits dropping of the extra reach rod 44, and during the dropping of the reach rod 44, the curved end 62 of the trip arm 26 presses against the roller 56, which causes the roller 54 that is positioned between the downwardly suspending arms 53-53 to move out of engagement with the recess 60 formed in the end of the pivoted arm 58, after which the socket members 46 and 48

swing on the pivot 50, as shown in Fig. 9, and at the time this operation takes place, the spring 40 pulling on the coupling rod 39 causes the upper reach rod 33 to break at the hinge 35, thus making the reach rods 33 and 36 inoperative and shutting off steam to the engine cylinder.

In case of overspeed of the engine, drop load or pulled switch, the electric magnet 11 loses its attracting forces, which allows the carrier rods 12 and 13 to drop downward to the position shown in Fig. 4, at which time, the extra reach rod 44 also drops down and the same operation takes place for making the reach rods 33 and 36 inoperative as described above in the case of the governor belt breaking.

While I have shown and described the preferred form of my invention, I realize that various minor changes may be resorted to, without departing from the spirit and scope of the invention as claimed; therefore, I do not wish to limit myself to the exact details of construction shown, nor to the combination and arrangement of parts.

What I claim as new and desire to protect by Letters Patent is:—

1. An automatic engine stop, comprising a pair of carrier rods adapted to be connected together, a pair of reach rods connected with intake valves, an extra reach rod and means for causing the reach rods to assume an inoperative position through the extra reach rod upon breakage of the governor belt.

2. In an automatic engine stop, a pair of carrier rods adapted to be connected together, a valve rocking lever, reach rods adapted to be connected with opposite ends of the valve rocking lever and the intake valves of the engine, means for connecting the reach rods and means for causing the reach rods to assume an inoperative position upon breakage or parting of the governor belt.

3. In an automatic engine stop, a ball governor, a governor belt, a pair of carrier rods supported on a governor standard, a valve rocking lever supported by the governor standard, reach rods connected with the opposite ends of the rocking lever and valve intake ports mechanism, a reach rod breaker positioned between one of the reach rods and the valve operating mechanism, an extra reach rod connected with the reach rod breaker and the carrier rod and means supported by the governor standard to allow the extra reach rod to drop downwardly and move the reach rod into an inoperative position upon breakage of the governor belt.

4. In an automatic engine stop, a ball governor, a governor supporting standard, a governor belt, an intake valve mechanism, a rocking lever supported by the governor standard, reach rods connected with the

valve rocking lever at one end and with the valve mechanism at the opposite end, a reach rod breaker positioned between the end of the lower reach rod and the valve mechanism, means for causing the reach rod breaker to break on parting of the governor belt and throwing the lower reach rod into an inoperative position and means for connecting the lower reach rod with the upper reach rod for moving the upper reach rod into an inoperative position upon breakage of the reach rod breaker in the lower reach rod.

5. In an automatic engine stop, a gov-

ernor, a supporting governor standard, a ¹⁵ governor belt, a supporting arm pivotally connected to the governor standard, a trip roller adapted to ride on the governor belt, a valve operating lever pivotally connected to the governor standard, reach rods connected with the valve lever and the valve mechanism of the intake port and the reach rods adapted to be moved into an inoperative position upon breakage of the governor belt.

20 25 In testimony whereof I affix my signature.

GEORGE C. BOOTON.
